BILLIARD CUE TIP FILE

Grigsby J. Fleshman, Oak Hill, W. Va.

Application June 17, 1946, Serial No. 677,315

1 Claim. (Cl. 69—20)

1

This invention relates to files and more particularly to a file which is particularly adapted for roughing the leather tip of a billiard cue.

An object of this invention is to provide a billiard cue tip file which will roughen the surface of a leather cue tip without pulling and tearing it and which is designed to be self-cleaning and will not become clogged by particles of leather from the cue tip.

Another object of this invention is to provide a billiard cue tip file which is formed of a series of parallel toothed blades, each tooth being pyramidal so as to provide a relatively fine filing groove.

Yet another object of this invention is to provide a billiard cue tip file having a series of parallel toothed blades and a deep groove between the blades, the groove between the blades being substantially greater than the groove between successive teeth on the same blade to prevent the filing grooves from becoming clogged.

Still another object of this invention is to provide a file of this kind which may be made in one piece, or built up from a series of parallel blades fixed together to form a file.

With the above and other objects in view, my invention consists in the arrangement, combination and details of construction disclosed in the drawings and specification, and then more particularly pointed out in the appended claim.

In the drawings, wherein similar reference characters designate similar parts throughout the respective views,

Figure 1 is a perspective view of a file constructed according to an embodiment of my invention.

Figure 2 is a vertical section taken on the line 2—2 of Figure 1.

Figure 3 is a side elevation, broken away, of an end of the file.

Figure 4 is a vertical section of a modified form of this invention.

Referring to the drawing, the numeral 10 designates generally a billiard cue tip file constructed according to an embodiment of my invention. The file 10 is formed of a series of parallel blades 11 fixed together in side abutting relation by welding as 12, or they may be secured together by screws or rivets, or any other suitable means for holding a series of blades 11 in this relation.

Each of the blades 11 is formed of an elongated body portion 14 and has a pointed triangular upper edge 15. The edge 15 is further formed with a series of upwardly divergent triangular notches 16, this forming a series of pyramidal teeth 17 on each blade 11.

Thus, when a number of blades 11 are secured together by welding 12 or any suitable attaching means, there is formed a file 10 having parallel

2

series of toothed blades 11, the teeth 17 of each blade so formed that there is formed a series of relatively deep longitudinal grooves 18 and finer transverse filing grooves 19 at right angles to the grooves 18, whereby the cutting action of the teeth 17 will remain free from the clogging particles of leather removed from the cue tip, the particles being free to move from the finer filing grooves 19 to the deeper longitudinal grooves 18 from which may fall freely from the file 10.

Such files are adapted for use in a billiard parlor where there are many such cue tips that require constant care, and so for attaching the file 10 to a suitable cord there is provided a ring 20 which may be attached to the file 10 through a suitable opening 21 in one end of the blades 11.

In Figure 4 there is shown a modified form of file. This file 22 is formed of an elongated rectangular body 24 having a series of parallel triangular grooves 25 longitudinally of the body 24 on one side thereof and a series of parallel filing grooves 26 at right angles to the grooves 25, transversely of the body 24, resulting in substantially the same file as shown in Figures 1 to 3.

I do not mean to confine myself to the exact details of construction herein disclosed, but claim all variations falling within the purview of the appended claim.

Having thus described my invention, what I claim is:

A cue tip file comprising a body comprising a series of longitudinally extending parallel cutting blades, each of said blades having a cutting edge of triangular cross section forming a series of parallel spaced apart longitudinal grooves between each of said blades, said blades formed with triangular teeth along the upper edge thereof, the teeth of adjacent blades being aligned transversely of said body forming a series of transverse longitudinally spaced apart pyramidal teeth on said body, said longitudinal grooves being of a depth greater than the height of said teeth whereby material removed by said teeth may pass freely from said file.

GRIGSBY J. FLESHMAN.
